UNITED STATES PATENT OFFICE.

FRANK N. KNEAS, OF NORRISTOWN, PENNSYLVANIA.

HANGER-SOCKET.

1,090,545.

Specification of Letters Patent. Patented Mar. 17, 1914.

Application filed January 27, 1910. Serial No. 540,874.

To all whom it may concern:

Be it known that I, FRANK N. KNEAS, a citizen of the United States, residing at Norristown, Montgomery county, Pennsylvania, have invented certain new and useful 5 Hanger-Sockets, of which the following is a specification.

Whether hangers be of heavy or light construction, and whether they be provided 10 with separate sockets or not, depend in large measure upon the character of the building and use intended, whether the matter to be supported was for duty or decoration, etc.

15 My invention relates to hangers of all of these types as well as to a large variety of forms of construction, and I have correspondingly varied the illustration, not with any attempt at showing all of the forms 20 with which it can be used, but to give some suggestion of its wide range, with the result that it would at once be evident in the mind of the expert in that art that it would apply to many other forms with which he was 25 familiar.

One of the purposes of my invention is to provide a space which is free from concrete above the socket, in line therewith, and to secure this end by means supported directly 30 upon the socket or upon some part intimately associated therewith.

A further purpose of my invention is to secure the hanger or socket or hanger socket to the mold board by means preferably capable of insertion from above the mold 35 board by unskilled labor, and of removal by like labor from beneath it; a matter of convenience at all times, and rendering it possible to withdraw this holder from the concrete while the latter is green with advantage 40 because of the character of the holder. I further provide for the projection of a pin or other suitable member through the socket and above it either to act as a guard 45 against undue encroachment of concrete, or to support a collar or cap for this purpose. Where the projection is itself the guard it may be made to "core" the space. I prefer to make such a projecting pin continuous 50 with the part which holds the hanger socket to the mold board, by which part, also I provide for initial retention to the hanger or hanger socket of a protective sheet, plate, washer, disk, or other protective facing preferably mounting the facing upon the part

permissibly performing either or both of these other functions. The character of the protective facing, where one is needed, will vary with the kind of destructive influence feared in that building, whether fire, acid, 60 alkali, rust, or other kind.

Where the guard against concrete encroachment at the top is preferably independent of any plug, pin or other like member, it is most desirably mounted upon the 65 socket itself, so that in my preferred form both the concrete spacing guard at the top and the protective facing are used, and both are initially connected with the hanger or hanger socket for shipment and placing. 70

The several features of my invention recited are independent of the character of socket used, whether it be the lower bar or part of the hanger, suitably threaded or otherwise adapted for connection to outside 75 parts, or a separate socket supported upon the hanger, or a combination of these forms.

A further feature of my invention, shown in the splitting of the dowel pin which I may use, is also independent of the character of socket. Other forms of pin, also, can be split. 80

In the drawings: Figure 1 is a vertical section through a hanger socket, retaining and protecting devices and mold board illustrating one form of my invention. Fig. 2 is a top plan view of the structure seen in Fig. 1 but omitting the mold board. Fig. 3 is a bottom plan view of the structure illustrated in Fig. 1 but omitting the mold board. Figs. 4 and 5 are vertical sections of sockets showing modified forms of concrete-spacing devices. Figs. 6-9 and 11-13 are vertical sections of a variety of forms of hangers, 85 sockets, concrete-spacers, hanger protectors and retaining devices by which I illustrate 90 my invention. Fig. 10 is a section upon line X-X of Fig. 9. Fig. 14 is a section upon line Y-Y of Fig. 12.

I have selected my illustrations of hangers etc. from forms which have proved to be cheap, practical and effective. 100

The length of the bolt, here taken as the typical form, by which outside connection is ultimately to be made with one of the 105 hangers or sockets is, of course, not known in advance, nor does the one selecting it always know the extent of the thread in the socket. Hence space must be provided for projection of the bolt through the socket, 110

which is preferably made by a guard to keep the concrete away from the socket. I make use of a different form of guard, or a guard differently mounted from that of other patentees. The hanger socket must also be secured to the mold board and I prefer to protect the otherwise exposed face of the hanger socket by novel means.

Considering the figures in detail, in Figs. 10 1, 2 and 3 I have shown a hanger 1 of general U shape and of uniform thickness, upon whose base 2 I rest a socket in the form of a nut 3, in this case recessed cylindrically at 4 to receive a cover 5 of desired height. The 15 cover is held in place, in this form, by a flange 6 upon it and by any suitable calking 7. Nuts counterbored in this manner are well known. In the form shown in Fig. 4 I show a somewhat similar counterbored 20 nut 3' in which a cover 5' is driven. In the form shown in Fig. 5 I have shown a plain nut 3², that is, not counterbored, but provided with an outer ring upon which is sprung or compressed a cover 5².

25 Again considering Figs. 1-3 particularly, both the hanger and the nut or socket are threaded so as to offer an extended surface for engagement by the bolt, suitable for heavy service if the normal size of each be maintained, or making possible the use of 30 thinner materials for the hanger to secure the same strength. The threading upon the hanger can here be omitted.

Beneath the hanger or yoke I place a 35 plate or sheet of facing material such as 8, which is preferably nonabsorbent or but partly absorbent, and which is proof against injury by fire, acid and alkali, in order that the socket may thus be fully protected. 40 Such a material is found in commercial forms of asbestos and in a variety of compositions of general cement composition, as well as in a number of other materials, particularly so-called insulating materials. I 45 show it substantially in the form of a washer and with the edge chamfered as at 9, so that the concrete shall itself grip and retain this facing. Where the facing initially used is intended for spacing purposes 50 only, to be removed with the mold board, the chamfering is preferably reversed, as in one of the other figures.

In the form shown on sheet 1 I make use 55 of a pin for a multifold purpose, to retain the parts of the hanger socket in fixed relation for shipment, handling and placing upon the mold board, to secure it to the mold board, and permit its removal therefrom from beneath the board, and, if it be desired 60 to use a very thin cover 5, to support this against excessive pressure. While there is coöperation between the structures and functions making the multifold purposes stated possible, it is evident that they are also each 65 valuable separately. Whether the forms of

hanger cover, face protector and pin operate together or separately the form and material of each may be greatly varied while still coöperating with the others.

The projection of the pin above the socket 70 or hanger may itself guard against concrete encroachment, or form the main or only support for a guard for that purpose.

I prefer to make the pin 10 from a plain cylindrical strip of wood, such as can be 75 purchased commercially in any lengths for dowel purposes, and to place what little thread there need be upon it by the act of screwing it into place. I prefer to split or kerf the pin for any desired distance, showing the slitting at the top in Fig. 1 and stopping it there before it passes through the mold board. This kerfing makes the top compressible to reduce its diameter and gives advantage from the spring of the material. I project the top of the pin at 12, 80 Figs. 1, 6 and 8 and use it as additional support for cover 5, as main support for collar 5², which could be a cover if desired, resting wholly upon the pin if necessary, or 85 make it the actual coring means as in Fig. 8. 90

The lower part of the kerf is shown at 13 beneath the protective facing so that an implement can be inserted to give purchase for screwing the pin into 95 and out of position. The lower part of the pin is preferably driven through the mold board far enough for the projecting part to be gripped in any suitable manner to unscrew the pin from below in the more usual 100 and desirable form of use of my invention, either before or after the concrete has set sufficiently to permit the removal of the mold board. There is considerable advantage in removing it while the concrete is green 105 where a bare pin at the top is used as the concrete does not attach so firmly to it then. However, oiling the top assists in preparing for removal. The mold board 15 is of any 110 suitable form.

In Fig. 6 I have shown the tops of the walls of the hanger 1' as flanged at 16 for further engagement with the concrete. Here the cover 5² is in the form of a screw collar supported largely if not entirely upon the 115 projecting part of the pin and open at the top at 17. Here I show a pin 10' with an enlarged base passing through the board 15' as seen at 14'. Above the board it forms a shoulder 18 upon which is rested a protective and spacing collar 19 partially closed at 20. This can be made of metal which is inert to any fumes or liquids from which protection is desired. Usually copper is best for it.

In all of the forms where the threaded 125 aperture is itself in danger of injury because of its exposure, it can be readily plugged with wood or closed or protected by other means.

In Fig. 7 I have shown spread walls for 130

the hanger 1² with a cover 5' and a preferably machine screw 21 headed at 22 within a washer 8' chamfered as at 9'. The cover is driven into an aperture 23 in a thickened base 2' so that no separate socket is needed. The base is threaded as seen, the whole forming a very desirable form of hanger with convenient retaining devices, including nails 24, except that it cannot be controlled in any 10 manner from below the mold board.

In Fig. 8 the hanger 1³ having base 2³ is provided with socket 3³ and is preferably screwed upon a pin 10² slotted to 13' and driven up from below the board leaving the 15 bottom of the pin 14² projecting. It may be prevented from turning, if this be necessary, by bar 14³ engaging a nail in the board.

In Figs. 9 and 10 the compound or composite hanger shown is made up of substantially parallel U shaped strips 25 united by cross pieces 26 and supporting a socket in the form of a bar 3⁴, within which pin 10³ is preferably screwed from below. The pin is then spread into suitable firm contact with 25 the walls of the hole in the board by any means such as nail or spike 27. It could be fastened transversely instead of by spreading, or could have a nut upon its lower part.

In the form shown in Figs. 11, 12 and 13 30 cylindrical hangers 1⁵, 1⁶ and 1⁷ are shown with bases 2⁵, 2⁶ and 2⁷. Base 2⁵ supports a socket 3⁵ circularly grooved at the top at 28 and projected at the bottom at 29. The sleeve 5⁴ rests in the groove and supports 35 the plate 30. The lower end 31 of the pin 10⁴ is slotted and driven into the board, while the upper end is threaded as at 32. 1⁶ is flanged through a part of its circumference, at least, as at 33 to be retained upon 40 the board by a double pointed nail having semicircular yoke 34 beneath projections 35 upon the hanger and having nail ends 36. The base 2⁶ of this form constitutes the socket.

45 In the form shown in Fig. 13 the socket is engaged by a metal screw 10⁵ pointed at 37 and the top of the hanger is closed by a plug 30'.

I have illustrated a sufficient number and 50 variety of forms of my invention to indicate

that the claims are entitled to a reasonable range of equivalents in their interpretation.

What I claim as new and desire to secure by Letters Patent is:

1. In a device of the character stated an 55 apertured flat base, a threaded socket resting thereon, upwardly extending spaced wings, separated throughout their lengths, attached to the outer edges of the said base, said base being wider than the socket so that the 60 wings are spaced beyond the socket, permitting plastic material to surround the socket and engage with the inner faces of the wings, a pin passing through the aperture of the base, engaging the socket and passing 65 above the socket to core the material within which the device is placed, and means upon the lower portion of the pin adapted to engage with a mold board.

2. In a device of the character stated, an 70 apertured flat base, a threaded socket resting thereon, upwardly extending spaced wings, separated throughout their lengths, attached to the outer edges of the said base, said base being wider than the socket so 75 that the wings are spaced beyond the socket permitting plastic material to surround the socket and engage with the inner portions of the wings, and a cap carried by and entering a recess in the upper part of the 80 socket and secured to the socket by the engagement with the inner walls of the recess.

3. In a device of the character stated, an 85 apertured flat base, a threaded socket resting thereon and having its upper surface exposed, upwardly extending spaced wings, separated throughout their lengths, attached to the outer edges of the said base, said base being wider than the socket so that the 90 wings are spaced beyond the socket permitting plastic material to surround the socket and engage with the inner faces of the wings, a pin passing through the aperture of the base, engaging the socket, and means upon the lower portion of the pin adapted to 95 engage with a mold board.

FRANK N. KNEAS.
